UNITED STATES PATENT OFFICE.

GEORGE W. DUNHAM, OF LANSING, MICHIGAN, ASSIGNOR TO OLDS MOTOR WORKS,
OF LANSING, MICHIGAN, A CORPORATION OF MICHIGAN.

CONTROLLER FOR MOTOR-VEHICLES.

968,750.

Specification of Letters Patent. Patented Aug. 30, 1910.

Application filed March 5, 1909. Serial No. 481,219.

To all whom it may concern:

Be it known that I, GEORGE W. DUNHAM, a citizen of the United States of America, residing at Lansing, in the county of Ing-
ham and State of Michigan, have invented
5 certain new and useful Improvements in
Controllers for Motor-Vehicles, of which the
following is a specification, reference being
had therein to the accompanying drawings.

10 The invention relates to control mechanism
for motor vehicles, being more particularly
designed for use as a speed controller,
and the invention consists in the construction
as hereinafter set forth.

15 In the drawings, the controller is illus-
trated in connection with a portion of a
motor vehicle shown in vertical longitudinal
section.

20 A is the dash of a motor vehicle, B the
foot board having the inclined portion C
at its forward end, as is usual in motor
vehicle constructions.

25 D is the steering stem of the vehicle, E
a hand controller shaft extending parallel
to the stem D, and F a rock arm connected
to a rock shaft G and operated from the
shaft E. This shaft G has connected there-
30 to the rock arm H, which in turn is con-
nected to the rod I extending to the throttle
valve J for the carbureter or other device
for varying the speed of the motor. There
is also a spring K connected to normally
hold the parts in position for low speed.

35 It is usual to provide a foot-actuated con-
troller in addition to the hand controller
by which the speed of the vehicle may be
altered, and this device is usually in the
form of a button, which may be depressed
40 by the operator's foot. It is, however, diffi-
cult to hold such a controller in different
positions of adjustment for the reason that
the oscillation of the vehicle tends to pro-
duce a corresponding variation of the op-
erator's foot. I have, therefore, devised a
45 construction of pedal having bearing por-
tions for the foot at different heights above
the foot board. This enables the operator
to produce any desired adjustment by first
shifting the foot to the proper bearing on
50 the pedal and then depressing the latter
until the foot is in firm contact with the
foot board, in which position it may be held
without difficulty.

As illustrated, L is a pedal which is ar-

ranged in a slot M in the inclined portion 55
C of the foot board. This pedal is provided
with an inclined and preferably slightly
concave bearing face N extending from the
fulcrum O to the extreme end. At the ful-
crum the face N is preferably substantially 60
on a level with the face of the foot board,
but from that point outward rises gradually
above the board until at the extreme end
it is sufficiently removed for the maximum
movement of the mechanism. On its lower 65
face the pedal N has a bearing upon a rock
arm P which is connected to the rock
shaft G.

With the construction as described, in
use the operator is permitted to rest his foot 70
upon the inclined portion C of the foot
board, and to control the pedal by shifting
the position of contact toward or from the
fulcrum. Thus, if the foot is moved out-
ward to the extreme end the maximum 75
degree of movement is imparted to the pedal
which operating through the rock arms P
and H, and rod I, adjusts the throttle valve
J to full open position for maximum speed.
Any degree of variation may be obtained 80
by shifting the foot rearward from this ex-
treme position, and in every case the sup-
port of the foot board will prevent oscilla-
tion of the foot by the vibration of the
vehicle.

85 What I claim as my invention is:

1. The combination with a foot board, of
a controller pedal fulcrumed at its rear end
and having a concave bearing face gradu-
ally inclining upward from the fulcrum to 90
the forward end of the pedal.

2. The combination with a footboard, of
a controller pedal having a bearing surface
in its normal position gradually inclining
upward from the plane of the footboard, 95
and having portions successively depre-
ssible to the plane of said board.

3. The combination with a footboard, of
a controller pedal having an inclined bear-
ing surface extending from the fulcrum to 100
the free end and in the normal position of
the pedal gradually inclining upward from
the plane of the footboard, said bearing
surface having portions successively de-
pressible to the plane of said footboard.

105 4. The combination with a footboard, of
a controller pedal fulcrumed at its rear end
having a bearing surface in its normal po-

sition gradually inclining upward from the plane of the footboard, and having portions successively depressible to said plane.

5. The combination with a footboard, of a pedal arranged in an aperture in said board, and provided with a bearing face inclining upward from the board, and having portions successively depressible to the plane of said board.
10. 6. The combination with a foot-board of a pedal arranged in an aperture in said board, and having a bearing portion inclining upwardly from the plane of the foot-board, said bearing having portions

successively depressible to the plane of said 15 board, and a rock arm arranged in the path of said pedal, beneath said board.

7. The combination with a footboard, of a controller pedal having bearing portions for the operator's foot normally at different 20 heights above said footboard and successively depressible to the plane thereof.

In testimony whereof I affix my signature in presence of two witnesses.

GEORGE W. DUNHAM.
